UNITED STATES PATENT OFFICE.

ABRAHAM KRAFT, OF FARMINGTON, MINNESOTA.

GRAIN-HARVESTER ATTACHMENT.

Application filed October 21, 1926. Serial No. 143,235.

The present invention relates to a novel structure, in the form of an attachment, for use in association with a grain harvester, and the principal object is to provide a device to be employed on the binder decking for saving grain and making straight well compressed bundles.

The usual binder deck is in two spaced sections and the compressing and trip mechanism operates between the adjacent portions of the sections. With the present day construction, the short pieces usually fall on the ground during the bundling operation, thus permitting loss of much material and the formation of a comparatively loose or ragged bundle.

The purpose of the improved invention is to hold all of the parts of the bundle together in such a manner as to permit them to be properly bundled and tied together, and to absolutely prevent the objectionable wastage referred to. With the improved attachment in place, about seventy-five percent of the otherwise scattered material is saved.

The specific structural features and advantages of the invention will become more readily apparent from the following description.

In the accompanying drawings forming a part of this application and in which like numerals are employed to designate like parts throughout the same:

Fig. 1 is a perspective view showing the invention in place for use on a conventional form of binder deck.

Fig. 2 is an enlarged perspective view of the invention per se.

Fig. 3 is a cross-section taken on the plane of the line 3—3 of Fig. 2.

Briefly, the invention comprises a sectional backing member which is hingedly mounted for downward and outward swinging on the discharge end of the deck, the same normally assuming a vertical operative position. Co-operating with one end of said backing member is novel means which is also associated with the customary needle arm, and this means acts in conjunction with the needle arm for moving the backing member to a position to facilitate discharge of the finished bundle at the proper time.

Referring now to the drawings in detail, it will be seen that the respective sections of the backing member are represented by the reference characters 1. Each section is

in the form of an elongated board. These are arranged in end to end spaced relation, the space being located in alignment with the slot existing between the parts 2 of the binder decking. The combined length of the two boards is, of course, consistent with the full width of the deck. It will be noticed from Fig. 1 that I have shown one of the packers 3 and the complemental trip 4, these being parts of the usual machine. In connection with the trip, I would state that free operation of the same is permitted by the curved connecting strap 5. This strap serves to produce simultaneous action of the two sections 1 of the backing board or member. The latter is fastened to the rear end of the deck by appropriate hinges 6, and these are so arranged as to allow a downward swinging of the boards. By directing attention to Fig. 3 in particular, it will be seen that a special bracket 7 is attached to the outer end of the right-hand board. This bracket comprises a pair of small plates 8 fastened to said board by bolts 9, and spacing sleeves 80 surround the bolts and are interposed between the plates to maintain them in the assembly represented. This bracket serves in a manner to be hereinafter made plain.

As before stated, novel means, broadly defined as a timing and operating device, co-operates with the bracket and the usual needle arm 11. This device is formed from a single length of wire of proper gage, and this is bent into a coil 12 between its ends. 90 One arm 13 is provided by the rearwardly extending end portion and this terminates in a right angular finger which is located between the aforesaid plates as indicated at 14. This makes for a loose yielding connection. The remaining end portion of the wire forms another arm 15 which also terminates in a right angularly formed finger located for operating contact with the arm 11. The compressor shaft 17 has a short 100 extension soldered or otherwise formed thereon and it is upon this that the coil 12 is rockably mounted.

From the foregoing, it is obvious that the wire operating member functions somewhat as a bell crank. In this connection it will be noted that at the proper intervals, the needle arm 11 will move upwardly through a limited arc. The inturned end 16 of the arm 15 being beneath the needle arm 11, will follow the needle arm, thus permitting the complemental arm 13 to

swing downwardly about the fulcrum coil 12. The loose sliding connection of the finger 14 in bracket 7 allows a free downward swinging movement of the member 1. When 5 the arm 11 returns to its normal position, it exerts a downward pressure on the finger 16, thus rocking the wire operating member back to the position shown in Fig. 1.

With this arrangement, it is obvious that 10 the resilient operating device is controlled by the needle arm, and at the proper time, the bundle backing board is allowed to swing down and permit discharge of the finished bundle. The resiliency of the operating device 15 also permits a required movement of the backing member while the bundle is in the making. In other words, if considerable pressure is brought to bear against the board while in a vertical position, the latter is 20 allowed to yield slightly owing to the formation of the arm 13 and the cooperating bracket 7.

It is thought that by considering the description in connection with the drawings, 25 a clear understanding of the construction and operation will be had. Therefore, a more lengthy description is deemed unnecessary.

I claim:

30 1. In combination, a binder deck, a needle arm, a compressor shaft, a bundle backing

member hingedly mounted upon said deck at the discharge end of the latter and adapted to assume a vertical operative position, and timing and operating means for said member pivotally supported at its center upon the shaft, having one end bearing against said needle arm and the other end slidably connected with said backing member. 35

2. In a structure of the class described, an attachment for the discharge end of a grain binder decking comprising a bundle backing member adapted to be hingedly mounted upon the decking, said member comprising a pair of duplicate boards of elongated form disposed in end to end spaced relation and an outwardly and longitudinally bowed connecting strap connected to the adjacent ends of said board, an operating device for said backing member comprising a single length of wire rod bent between its ends to provide an attaching and fulcrum coil, the portions extending from said coils forming operating arms, said operating arms terminating in 55 right angularly disposed fingers, one finger being adapted for association with a needle arm, and the brackets carried by one of the aforesaid boards, the remaining finger being connected with said bracket. 60

In testimony whereof I affix my signature.

ABRAHAM KRAFT.
